UNITED STATES PATENT OFFICE.

JOHN D. BRETT, OF CORDELE, GEORGIA.

AXLE JOURNAL AND HUB.

NO. 921,073.

Specification of Letters Patent.

Patented May 11, 1909.

Application filed December 19, 1908. Serial No. 468,365.

To all whom it may concern:

Be it known that I, JOHN D. BRETT, a citizen of the United States, residing at Cordele, in the county of Crisp, State of Georgia, have invented certain new and useful Improvements in Axle Journals and Hubs; and I do hereby declare the following to be a full, clear, and exact description of the invention, such as will enable others skilled in the art to which it appertains to make and use the same.

This invention relates to improvements in axle journals and vehicle hubs, and has for one of its objects to improve the construction and increase the efficiency and utility of devices of this character.

Another object of the invention is to provide a simply constructed device wherein the introduction of the lubricating material is facilitated and the journal and hub less liable to run "dry".

The invention further consists in certain novel features of construction, as hereafter shown and described and then specifically pointed out in the claims, and in the drawings illustrating the preferred embodiment of the invention, Figure 1 is a plan view of the hub and a portion of the axle with the improvement applied. Fig. 2 is a longitudinal sectional elevation of the parts shown in Fig. 1. Fig. 3 is a transverse section on the line 3—3 of Fig. 2. Fig. 4 is a perspective view of the outer sand band of the hub detached with the improved attachment for applying the lubricating material to the outer portion of the hub.

The improved device may be applied without material structural changes to axles of various sizes, and to axles employed upon various kinds of vehicles, and it is not desired therefore to limit the invention to any specific form of axle or to axles employed for any specific form of vehicle.

For the purpose of illustration the improvement is shown applied to a conventional axle, a portion of which is represented at 10 and provided with a journal 11 having a reduced outer threaded end 12. The hub of the vehicle is represented at 13 and provided with an internal box 14, the box being shorter than the internal bore of the hub, as shown. The inner end of the hub is provided with a sand band 15 extending rearwardly over the adjacent portion of the axle, as shown.

Bearing around the outer end of the hub

is a holding band 16, and bearing over this holding band is an outer sand band 17, the latter extending beyond the outer end of the hub and over the holding nut. 60

Bearing within the inner end of the hub is a sleeve 18, and formed with a reduced end bearing within the adjacent portion of the box 14, the sleeve having an external flange 19 bearing against the rear or inner 65 end of the hub.

Bearing around the journal 11 next to the axle stock 10 is a sleeve 20, this sleeve extending between the sleeve 18 and the journal as shown, and provided with a lateral 70 flange 21 extending between the flange 19 and the adjacent portion of the axle.

Passing through the outer end of the axle 10 adjacent to the flange 21 and likewise extending through the same is a feed pipe 22 75 through which lubricating material is fed to the journal, the inner end of the tube 22 discharging against the flanges 19—21 and thence between the sleeves 18—20 and so into the space between the journal and the 80 box 14 and thus lubricate the journal.

Supported within the outer end of the hub 13 is a sleeve 23 having a reduced inner end and extending within the outer end of the box 14, and likewise provided with a 85 flange 24 bearing against the outer end of the hub.

Mounted upon the journal 11 within the sleeve 23 is another sleeve 25 having an external flange 26 bearing against the outer 90 face of the flange 24.

The flange 26 is provided with two spaced lugs 27—28, and fitting over the other terminal 12 of the journal is the holding nut 29, the nut having cavities to receive the 95 studs 27—28, and thus effectually prevent the sleeve 25 and its flange 26 from running backwardly off from the journal.

The holding nut 29 is provided with a threaded aperture in its outer face in which 100 a threaded stud 30 is inserted, the stud provided with a screw driver cavity whereby it may be adjusted through the outer end of the sand band 17. By turning the screw in one direction the movement of the nut 29 105 may be controlled to prevent lost motion or looseness, and by rotating the screw still further the nut may be firmly locked in position.

Formed in the exterior of the outer sand 110 band 17 are two pairs of slots 31—32 spaced apart, and formed through the sand band

near the slots 32 is a cavity 33, through which oil may be inserted around the flanges 24-26, and percolates between these flanges and thence to the journal as hereafter explained.

Slidably disposed over the outer surface of the band 17 is a relatively short plate 34 having lugs 35 extending through the slots 31-32 and adapted to be clenched beneath them, to couple the plate 34 to the band 17, and permit it to move circumferentially of the band for a distance equal to the range of the slots.

Connected to the plate 34 by a rivet 36 or other suitable fastening means is a relatively long plate 37, the latter having an aperture 38 adapted to register with the aperture 33 when the plates 34-37 are disposed in one position and to be located opposite the solid or unperforated portion of the band when the plates are disposed in another position.

When the plates are adjusted with the lugs at one end of the slots 31-32 the aperture 38 will be opposite the solid portion of the band and then when the plates are adjusted with the lugs at the opposite end of the slots the aperture will register with the aperture 33. When the apertures are thus in registering position it will be obvious that the discharge nozzle of an oil can can be inserted to apply lubricating material to the joint between the flanges 24-26, and thus supply lubricating material to the journal, as the oil will percolate behind the flange and find its way into the cavity between the journal and the box. Thus the lubricating material may be readily applied at both ends of the journal.

The lugs 27-28 operating in the cavities in the holding nut 29 and the oil pipe 22 serve to hold the sleeves 25-20 from rotating, and thus confine the friction between the sleeves 23-18 and the sleeves 25-20.

The improved device is simple in construction, can be inexpensively manufactured, and produces a very efficient axle and hub which may be readily lubricated without removal from the journal.

What is claimed is:—

1. The combination with an axle and its journal, the journal having a threaded terminal, of a hub having an internal box of less length than the hub, a sleeve within the hub at each end and extending into the box and with flanges bearing against the ends of the hub, a sleeve bearing over the journal at each end and within said hub engaging

sleeves and with flanges bearing against the flanges of the same, and a holding nut engaging the threaded end of the journal and bearing against the flange of the adjacent journal sleeve.

2. The combination with an axle and its journal, the journal having a threaded terminal, of a hub having an internal box of less length than the hub, a sleeve within the hub at each end and extending into the box and with flanges bearing against the ends of the hub, a sleeve bearing over the journal at each end and within said hub engaging sleeves and with flanges bearing against the flanges of the same, the flange of the outer journal sleeve having spaced lugs, and a holding nut engaging the threaded end of the journal and bearing against the flange of the adjacent journal sleeve and provided with cavities to receive said lugs.

3. The combination with an axle and its journal, the journal having a threaded terminal, of a hub having an internal box of less length than the hub, with a sand band at the outer end thereof and provided with a transverse oil aperture, a shield carried by the band and movable over said oil aperture, a sleeve within the hub at each end and extending into the box and with flanges bearing over the journals at each end and within the said hub engaging sleeves and with flanges bearing against the flanges of the same, and a holding nut engaging the threaded end of the journal and bearing against the flange of the adjacent journal sleeve.

4. The combination with an axle and its journal, the journal having a threaded terminal, of a hub having an internal box of less length than the hub, a sleeve within the hub at each end and extending into the box and with flanges bearing against the ends of the hub, a sleeve bearing over the journal at each end and within said hub engaging sleeves and with flanges bearing against the flanges of the same, a cap nut engaging over the threaded end of the journal and bearing against the flange of the adjacent journal sleeve, and a screw pin operating through the cap nut and engaging against the end of the journal.

In testimony whereof, I affix my signature, in presence of two witnesses.

JOHN D. BRETT.
